CLAIM

The ornamental design for an automatic toothpaste tube dispenser, as shown and described.

DESCRIPTION

FIG. 1 is a front, top and side perspective view of the automatic toothpaste tube dispenser embodying the design of the present invention;

FIG. 2 is a front elevational view thereof, the rear opposite being a mirror image of the front shown in FIG. 2;

FIG. 3 is a left side elevational view thereof;

FIG. 4 is a right side elevational view thereof;

FIG. 5 is a top plan view thereof; and,

FIG. 6 is a bottom plan view thereof.
